HAND STAMP

Paul A. MacPhee and George T. Brown, Jr., Dayton, Ohio, assignors to The National Cash Register Company, Dayton, Ohio, a corporation of Maryland

Application February 15, 1950, Serial No. 144,365

15 Claims. (Cl. 191—327)

1

This invention relates to a hand stamp, and more particularly pertains to one having an ink-impregnated porous resilient type member and an adjustable shield, or shields, by use of which a selected portion, or portions, of the type may be covered and displaced and thus prevented from coming in contact with the record material or article on which an impression is to be made.

This invention finds its most important use in adding positional code information to that given by the type characters. For instance, if the type data on the stamp was a numerical digit with an accompanying design pattern, such as a surrounding ring which will be used in describing the preferred embodiment of the invention, a portion of such pattern could be prevented from appearing on a printed impression at a positional point, or points, depending on the selective positioning of one or more shields.

Inasmuch as in the preferred embodiment the ink supplied for the printing comes from within the type member itself, the shield, or shields, are positioned so as to prevent the portions of the type character selected for deletion from coming in contact with the record material. By reason of the ink coming from the porous printing member itself, repeated printing operations of the same data may be made without moving the shields.

The preferred form of the invention will be described in connection with a price marking stamp which prints the price on an article and at the same time prints coded data thereon by the selective position of a shield or shields on a pattern to be printed with the price. Thus, such data as the time of marking the article, its source, its cost, the store identification, and the like, may be code-marked thereon.

As stated, the preferred embodiment of the invention utilizes a ring surrounding the price mark because first, the shields may be easily moved around to cover any selected part of the ring and, second, because all people are familiar with the points of a circle as marked on a clock face and can estimate hour positions on a circle accurately. Also, hour positions can be translated into month positions, if such unit of time is used, as there are twelve month positions which correspond to the hour positions. Thus, the "3" hour position on a ring, evidenced by a break in the ring at that point could mean the month "March."

The invention, however, is not to be deemed limited to the ring pattern as dots, scallops, polygons, radial lines and small letters and numbers, may be used instead.

2

Therefore, it is an object of this invention to provide a hand printing stamp with means to shield selected portions of the printing surface from contact with record material or articles to be printed.

Another object of the invention is to provide such a stamp in which the printing ink is supplied from pores within the stamp.

With these and incidental objects in view, the invention includes certain novel features of construction and combination of parts, a preferred form or embodiment of which is hereinafter described with reference to the drawing which accompanies and forms a part of this specification.

15 In the drawing:

Fig. 1 is the printing end of a price marking stamp showing a single selectively operable shield cooperating with the porous printing member, the shield being positioned to cover the 9 position on a ring character surrounding the price character,

20 Fig. 2 is a vertical section through the substance of Fig. 1 on a line through the 9 and 3 positions and cutting across the middle of the numerical digit 1 shown as the price character,

25 Fig. 3 is a perspective view of the whole printing stamp of Figs. 1, 2 and 4, showing the printing surface of the porous type member,

Fig. 4 is a top end view of the stamp of Figs. 1, 2 and 3,

30 Fig. 5 is an impression made by the stamp of Figs. 1, 2, 3 and 4 without the shield,

Fig. 6 is an impression made by the stamp of Figs. 1, 2, 3 and 4 with the shield in place and covering the 9 position,

35 Fig. 7 is a perspective view showing a modified form of the invention in which two shields are used, and

Fig. 8 is an impression made by the stamp of Fig. 7 as the shields are shown adjusted therein.

40 Referring to Figs. 1, 2, 3 and 4, there is shown a commercial hand printing stamp, widely used in marking prices on articles in grocery stores, and consisting of a wooden handle 20, with a conical end 21, having a circular well 22, in which is secured an ink impregnated porous rubber printing type 23 having a numerical type character 24 in relief, representing the numerical digit 1. Surrounding the type character 24 is a ring 25 in the same height relief as character 24, which together ordinarily would make a printed ink impression like Fig. 5 when applied to record material or an article, the ink being internally supplied from the pores.

45 50 55 A spring collar 26, resiliently embracing the conical head 21 enabling it to be turned thereon

and also enabling it to be moved toward the point of the conical end 21 during a turning operation, has a spring arm 27 ending in a curved finger-like shield 28. The spring arm 27 is given a set so that shield 28 will engage the ring 25 at any turned adjustment of collar 26 providing the collar is moved away from the pointed end of the cone 21 from the position shown in Figs. 1, 2 and 3. In making a turning adjustment of the collar it is moved slightly toward the point of the conical end which lifts finger 23 off the ring and allows for circular adjustment of the collar without frictional rubbing of the ring by the finger.

An indicator formation 29 may be provided on the collar for use in connection with appropriate designations on the conical end of the printing member handle to aid the user in accurate positioning of the finger. The drawing shows the indicator set at 9 on a series of twelve equally placed digit designations around the conical end. This corresponds to the shown finger setting which makes a break in the inked impression made thereby as shown in Fig. 6. Various adjustments may be made to locate the break at any place on the ring.

A modified form of the invention is shown in Fig. 7 wherein the stamp handle 31 has an end 32 of cylindrical shape, of larger diameter than the rest of the handle, in which is cut a groove 33 embraced by two rotatably adjustable collars 34 and 35, equipped respectively, with spring arms 36 and 37 and finger shields 38 and 39 which in the adjusted position shown make the printed mark of Fig. 8. These collars may be adjusted individually around the handle to cause the selective positioning of two breaks in the ring printed by the stamp.

It will be apparent that it is necessary that the type members, or at least the characters, be resilient so that when an impression is made the fingers may sink thereinto allowing the printing surface of the characters to touch the article to be printed unimpeded, the type under the fingers being displaced.

It is to be understood that any type characters other than the "i" illustrated may be used within the ring or with other formations substituted in place of the ring.

It is to be understood, also that the printing member described may be operated by a machine to which it is attached, if such be desired.

What is claimed is:

1. A printing device including, in combination, a resilient printing type adapted to be impregnated with ink, thereby to make an ink impression on contact with record material, said type having characters in relief thereon to form printing surfaces and the printing surfaces of said characters forming a printing plane; and a shield mounted on the device and movable thereon both parallel to and normal to said plane, to cover and displace desired areas of the type printing surfaces so that such covered and displaced areas will not make a printing impression.

2. A printing device including, in combination, ink-impregnated resilient type having characters in relief thereon to form printing surfaces, thereby to make an inked impression on contact with record material, the printing surfaces of said characters forming a printing plane; and a shield mounted on the device and movable thereon both parallel to and normal to said plane, to cover and displace desired areas of the type printing

surface, so that such covered and displaced areas will not make a printing impression.

3. A printing device including, in combination, ink-impregnated resilient porous type having characters in relief thereon to form printing surfaces, thereby to make an inked impression on contact with record material, the printing surfaces of said characters forming a printing plane; and a shield mounted on the device and movable thereon both parallel to and normal to said plane to cover and displace desired areas of the type printing surface, so that such covered and displaced areas will not make a printing impression.

4. A printing device including, in combination, resilient printing type adapted to be impregnated with ink, said type having relief formations representing standard data and other relief formations representing a choice of data, said relief formations having printing surfaces forming a printing plane; and a shield means movably mounted on the device and adjustable by movement parallel to and normal to said plane to cover and displace a desired portion of said other relief formations of the type printing surface, so that such covered and displaced areas will not make a printing impression.

5. The printing device of claim 4, in which said other relief formations comprise a ring surrounding the standard data relief formations.

6. The printing device of claim 4, in which said other relief formations surround the standard data relief formations.

7. The printing device of claim 4, in which said other relief formations are arranged about the standard data relief formations.

8. The printing device of claim 4, in which the shield means comprises a non-printing finger of an area less than said other relief formations and mounted so as to be movable over said other relief surfaces from place to place, as desired.

9. The printing device of claim 4, in which the printing type is porous.

10. The printing device of claim 4, in which the type is porous and ink-impregnated.

11. A hand stamp including, in combination, a handle; a porous resilient printing type member attached to the handle, said printing type member having characters in relief thereon, the printing surfaces of said characters forming a printing plane, and said porous printing type member adapted to be impregnated with ink thereby to make an inked impression on contact with record material; and a shield member mounted on the handle and selectively movable on the handle, both parallel to and normal to said printing plane, to cover and displace a selected area of the type member to prevent said selected area from printing.

12. The hand stamp of claim 11, in which the shield member includes a collar resiliently embracing the handle and movable around it, said collar having a non-printing finger movable with said collar to cover and displace different portions of the printing surface of said type member.

13. The hand stamp of claim 12, in which the collar also is shiftable on the handle to raise the finger off the type member while the collar is being adjusted around the handle.

14. The hand stamp of claim 11, in which the type member has numeral data in relief thereon and a ring in relief around the data over which ring the shield is selectively movable.

15. The hand stamp of claim 11, in which the type member is impregnated with ink.
